CLAIM

The ornamental design for a coordinate input device, as shown and described.

DESCRIPTION

FIG. 1 is a front-right-bottom perspective view of a coordinate input device according to an embodiment of my new design;

FIG. 2 is another front-right-bottom perspective view thereof;

FIG. 3 is a rear-left-top perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof;

FIG. 9 is a bottom plan view thereof; and,

FIG. 10 is an enlarged partial front-right-bottom perspective view thereof as indicated in FIG. 2.

The dashed indicator line enclosing area “10” in FIG. 2 is for reference to the enlarged view only and forms no part of the claim. The dash-dot-dot broken line in FIG. 10 shows the extent of the enlarged view only and forms no part of the
